JOHN A. VAN DEN BROEK, OF ANN ARBOR, MICHIGAN

SPIRAL SPRING

Application filed February 13, 1931. Serial No. 515,580.

My invention relates to improvements in spiral springs and their use and is designed to eliminate the contact of the various convolutions of such springs, and the consequent friction resulting from such contact, when such springs are stressed.

I attain this objective by mechanism illustrated in the accompanying drawing, in which Figure 1 is a view of two spiral springs curved in reverse directions, the outer ends AA' being connected by bar B to which they are rigidly connected. Figure 2 is a view of two spiral springs, curved in opposite directions, superimposed one on the other. Figure 3 is a view of a single spiral spring with the outer end attached to a movable bar as hereinafter described.

For the purpose of the description which follows, I define a spiral spring as an elastic bar permanently curved in such a way that a point moving along it, or along its projection on a plane, would revolve about a fixed point, here called the inner end or center, while at the same time departing from that center, and of sufficient length so that a straight line between that center and the outer curve of the bar will intersect the bar more than once. The outer end of the spring I define as the point where the spiral as above defined ceases, either because of the termination of the bar itself, because of a material change in its direction, or because the spring starts to approach the center instead of departing from it. The inner end of the spring I define as the center of the spiral, regardless of whether or not the spring terminates before the center is actually reached.

I have discovered what has heretofore been unknown as a feature of spiral springs, namely, that if the ends of the spring be permitted freedom of motion in radial relation to each other, while at the same time the tangent of the curve at the outer end is held in constant angular relation to the straight line connecting the ends, the spring can be stressed by coiling or uncoiling without causing the several coils of the spring to lose their relative concentricity, and in consequence, without causing the points of the spring along any one radius to come into contact sooner than do

the points along other radii. In other words, my discovery is one whereby the friction in the coiling or uncoiling movement of the spring caused by the contact of the several coils of the spring while it is being coiled or uncoiled can be avoided. This tendency of a spring to retain the relatively concentric position of its coils while under stress can be produced only by permitting a free movement of the two ends in linear relation to each other, while at the same time maintaining the tangent to the curve of the outer end in constant angular relation to the straight line connecting it with the inner end.

This freedom of radial movement coupled with the maintenance of constant angular relation of the tangent can be accomplished in various ways. Figure 1 of the accompanying drawing, for example, shows two spiral springs curved in reverse directions, the outer ends AA' being connected by bar B to which they are rigidly connected. If, now, these springs be simultaneously stressed by rotating the tangents to the inner ends CC' in opposite directions, the radial distances AC and A'C' will be reduced. At the same time the connecting bar B will maintain the tangents at the points AA' in constant relation to the radii CA and C'A'. Conversely, when the torque at the points C and C' is decreased and the springs are allowed to resume their normal shape, the radii CA, C'A' will increase in length while the relation of the tangents at A, A' to the radii is maintained constant by the bar B.

Figure 2 of the accompanying drawing is another illustration of the application of my discovery. Here two spiral springs X and Y, curved in opposite directions, are superimposed one upon the other. If the inner end of spring X be held fixed, while the tangent to the inner end of spring Y be rotated, the outer end A of spring Y will be caused to move in a circular path. This point is, however, connected to the outer end A' of spring X. The movement of the end A caused by the rotation of the inner end of spring Y causes a circular movement of A', the outer end of spring X. The elastic resistance of spring X, however, prevents

the free motion of points A and A', and causes both spring X and spring Y to change their normal shape. In other words, the rotation of the center of spring Y causes both 5 spring Y and spring X to be stressed. As this rotating, or stressing, process continues, the outer ends A and A' continue to move in a curved path, but at the same time they are free to lessen or increase the radial distance between themselves and the centers of 10 their respective springs. If the connection of the outer ends A and A' be of such a nature as to prevent the tangents of these two ends from moving in relation to each other, 15 it will also maintain the tangents in constant relation to the line between them and the respective centers.

Another method is a single spring (Figure 20 3), the outer end, A, of which is rigidly fastened to a rigid bar, B, said bar being in contact with a perpendicular pin at the center C. This bar is free to move against such pin, but is prevented from angular motion by another 25 pin, D, somewhere outside the periphery of the spring. As this spring is stressed by rotating the tangent of the inner end, the outer end, A, is prevented from movement in a curved path by contact of the bar against the two pins mentioned. As this contact, 30 however, does not prevent longitudinal movement of the bar, the end A is free to approach the inner end or to depart from it, but the tangent at A because of the rigidity of the connection of the end A and the bar 35 B will be maintained in constant relation to the line from A to C.

These illustrations are given only for the sake of illustration, and while I claim them specifically, I do not limit my claims to the 40 particular forms thus explained.

Spiral springs embodying my invention have a definite advantage over those not embodying it, in this respect:—When a spiral spring is put under stress, either by holding 45 the inner end in a fixed position and moving the outer end in a curved path, or by holding the outer end in such a way as to prevent movement in a curved path and rotating the tangent of the inner end in a curved direction, the strain at different points along the 50 curve of the bar varies; that is to say, the stress is not uniformly distributed throughout the length of the bar. When this occurs, if the ends of the spring are maintained at 55 a permanently unchanging linear distance from each other, the coils tend to change their normal unstressed shape in relation to the center, and to lose their true spiral configuration. Those parts in the line of one 60 radius from the center tend to be thrust away from the center, while those parts along the opposite radius tend to be thrust toward the center. As this condition is exaggerated, those points along the latter radius eventually are brought into juxtaposition with each 65

other. As the movement of the coils is continued after these parts have come into contact, a friction between these contact points is created. By my discovery that the tendency of the coils to assume an eccentric position can be markedly lessened by allowing the ends of the spring free movement in their linear distance from each other while maintaining the tangent of the outer end in constant angular relation to the straight line 75 connecting it with the inner end, I am able practically to eliminate this friction.

I claim:—

1. The combination of a spiral spring, means for stressing said spring to produce 80 coiling or uncoiling of the spring, while permitting the linear distance between the ends of the spring to change, and means for maintaining the tangent to the curve of the outer end of the spring in constant relation to the straight line between it and the inner end during such coiling or uncoiling operation.

2. The combination of two spiral springs, means for stressing one or both of said springs to produce coiling or uncoiling of the springs, and means for attaching an end of one spring to an end of the other in such a way as to maintain the ends so attached in constant tangential relation to each other while leaving them free to vary their linear 95 distance from the other ends of the springs during said coiling or uncoiling operation.
